Des. 223,476
Patented Apr. 18, 1972

223,476

WRITING IMPLEMENT HOLDER

Roland Longarzo, Valley Stream, N.Y., assignor to Consolidated Foods Corporation, Chicago, Ill.

Filed Sept. 18, 1970, Ser. No. 25,319

Term of patent 14 years

Int. Cl. D19—02

U.S. Cl. D74—5

FIG. 2

FIG. 1

FIG. 3

FIG. 4

FIG. 5

FIG. 6

FIG. 1 is a top plan view of a writing implement holder showing my new design;

FIG. 2 is a rear elevation;

FIG. 3 is a side elevation;

FIG. 4 is a front elevation;

FIG. 5 is an elevational view of the side opposite to FIG. 3; and

FIG. 6 is a bottom plan view thereof.

I claim:

The ornamental design for a writing implement holder, substantially as shown.
